UNITED STATES PATENT OFFICE

99,333

DESIGN FOR A BOTTLE OR SIMILAR CONTAINER

Arthur E. Rowse, Lexington, Mass.

Application January 3, 1936, Serial No. 60,407

Term of patent 7 years

To all whom it may concern:

Be it known that I, Arthur E. Rowse, a citizen of the United States, residing at Lexington, in the county of Middlesex and State of Massachusetts, have invented a new, original, and ornamental Design for a Bottle or Similar Container, of which the following is a specification, reference being had to the accompanying drawing, forming part thereof.

The drawing is a front view of the container, the opposite of the design being substantially plain.

I claim:

The ornamental design for a bottle or similar container, substantially as shown and described.

In testimony whereof, I have signed my name to this specification.

ARTHUR E. ROWSE.
